(57) **CLAIM**

The ornamental design for a wrist orthosis as shown and described.

DESCRIPTION

FIG. 1 is a perspective view of a wrist orthosis, shown in condition of use;

FIG. 2 is a front view of the wrist orthosis of FIG. 1;

FIG. 3 is a right view thereof;

FIG. 4 is a rear view thereof;

FIG. 5 is a left view thereof;

FIG. 6 is a perspective view of the wrist orthosis of FIG. 1, shown in condition of use;

FIG. 7 is a top view of the wrist orthosis of FIG. 1; and,

FIG. 8 is a perspective view thereof.

The claimed design shows an organically-shaped orthosis. In the drawings, the broken lines depict portions of the orthosis and form no part of the claimed design. The broken lines showing a hand in FIGS. 1 and 6 depict environmental subject matter and form no part of the claimed design. The dash-dot-dash broken lines define the bounds of the claim. All broken lines form no part of the claimed design.
